PAUL GOFFART, OF BRUSSELS, BELGIUM, ASSIGNOR, BY MESNE ASSIGNMENTS, TO
BELGIAN AMERICAN COKE OVENS CORPORATION, OF WILMINGTON, DELA-
WARE, A CORPORATION OF DELAWARE.

COKE OVEN.

Application filed March 10, 1920. Serial No. 364,645.

To all whom it may concern:

Be it known that I, PAUL GOFFART, a subject of the King of Belgium, and resident of Brussels, Belgium, have invented certain 5 new and useful Improvements in Coke Ovens, of which the following is a specification.

My invention relates to coke ovens, and has for its object to secure improved results 10 in the production of coke, particularly from coal high in volatile constituents. Speaking generally the invention constitutes an improvement upon the known type of oven in which the side walls of the cooking chambers 15 contain upright heating flues, and during one stage of the operation, the gases travel upwardly in the flues at one-half of the said wall, then horizontally in a top channel, and then downwardly in the flues at the other 20 half of the heating wall, while during the next stage of the operation, the flow of the gases is reversed; but during either stage, the direction of flow is the same for all the heating flues at the same half of the heating 25 wall.

I have found that an oven of the construction referred to is quite satisfactory for coking ordinary coal, but yields less acceptable results with certain types of coal having but 30 a slight agglutinating power while containing a high percentage of volatile matter. In order to convert coal of these types into dense coke, it is important to insure a rapid distillation at the top of the charge, so that 35 the volatile matter developed from the lower portion of the charge will not cause the production of spongy coke at the upper portion thereof.

In order to obtain this result, I have devised the following novel features 40 distinguishing my improved coke oven from others and particularly from those of the type to which I have referred.

First, the upright heating flues of a heating 45 wall have been divided into independent groups each comprising two adjacent flues. The heating gas or fuel is admitted continuously at the top, at a point between the two flues of the same group; the 50 air for supporting combustion travels upwardly in one flue of each group, and the gases resulting from the combustion of said fuel with the aid of said air pass down in the other flue of each group; from time to

time, the direction of flow of air and of 55 combustion products is reversed in said flues, that is to say, each flue of a pair or group is alternately used for the upward travel of air to support combustion, and for the downward travel of combustion gases. 60

Second, a regulation may be effected both as to the length of the flame and the intensity as well as the point of application of the heat to the charge under treatment; for this purpose the air for supporting combustion 65 is supplied in regulatable amounts at different levels of the heating wall, through openings of proper location and cross section provided in the partition separating the two heating flues of the same group. 70

Third, at a level below the sole of the cooking chambers, I place two sets of channels or flues extending the full length of the oven, the channels of one set being located directly beneath the respective coking chambers and being connected with alternate heating flues of an adjacent heating wall and also with one of the regenerators, while the channels of the other set are located directly under said heating wall and are connected 80 with the other heating flues of the same wall and also with the other regenerator. 75

In the accompanying drawings I have illustrated, as an example, a coking oven embodying my invention. Fig. 1 is a vertical 85 section taken lengthwise through one of the coking chambers; Fig. 2 is a similar section taken lengthwise through one of the heating walls, and Figs. 3 and 4 are vertical cross sections taken on lines A—B and 90 C—D respectively of Fig. 2.

The heating walls *g* located at both sides of the longitudinal coking chambers *h* contain upright heating flues 3, 4 arranged in a plurality of consecutive pairs, the two 95 flues of the same pair being separated by a perforated partition *i*, while adjacent flues 3, 4 of different pairs are separated by imperforate partitions *j*, so that each pair is separate from the other pairs. Each perforated partition *i* is provided with one perforation or opening *d* at the top, and with 100 one or more additional perforations, such as *d'*, *d''*, at different levels. As will be seen in Figs. 3 and 4, the perforations decrease 105 in width, or at least in cross section, from the upper perforation *d* to the lower perforation *d''*. Fuel (gas) is admitted to the

central portions of the perforations or openings *d*, through nozzles *a* provided with cocks or valves enabling the amount of gas to be regulated for each nozzle individually. This 5 gas is fed through the nozzles continuously, irrespective of the periodical reversal, which affects only the air supply and the combustion products. The lower ends of the flues 3 are connected by ducts 2 with horizontal 10 channels 1 located directly beneath the respective heating walls, at a level below the sole of the coking chambers. At one end of the oven, each channel 1 communicates with the top of a primary regenerator *b*, 15 the bottom of which is connected in a well known manner with a secondary regenerator *c* of less height, the upper portion of which is connected with a reversing valve of well known type, and according to the position 20 of said valve, the upper portion of the secondary regenerator *c* is connected either with the chimney to discharge combustion gases into the same, or with air heating 25 channels *e*, *f*, located respectively above the secondary regenerators *c* (and *c'*) and below all the regenerators, so that air from said channels *e*, *f*, which are open to the surrounding air at one end may in that case 30 pass successively to the secondary regenerator *c* and the primary regenerator *b*. Alternating with the channels 1 is another set of similar channels 6, each located directly 35 beneath one of the coking chambers *h* and connected, at the end of the oven opposite to the regenerator *b*, with a similar primary 40 regenerator *b'*. The upper portion of each channel 6 is connected, by inclined or angular ducts 5, with the bottom portions of the several heating flues 4 of an adjacent heating wall *g*. A secondary regenerator *c'* is 45 related to the primary regenerator *b'* and to the reversing valve in the same manner as explained above in connection with the regenerators *b* and *c*.

50 The operation will be understood readily. During one stage, the air (having passed through the channels *e*, *f*) travels successively through the connected regenerators *c* and *b* to enter the sole channels 1 from which it rises, in a heated condition, in the ducts 2 and flues 3. Through the graduated openings *d*, *d'*, *d''*, the air passes into the corresponding flues 4 of each pair; to which gas is supplied at the top (in the opening *d*), through the nozzle *a*. Combustion 55 thus takes place in the flues 4, the combustion gases traveling downwardly in such flues to reach the ducts 5 leading to the channels 6. From these channels the gases

pass successively to the regenerators *b'* and *c'* to heat them and then through the reversing valve to the chimney. After a suitable time, the position of the reversing valve is changed, and during the subsequent stage the air from the channels *e*, *f*, passes 60 through the previously heated regenerators *c'* and *b'* to the channels 6 and ducts 5, rises in the flues 4 and passes through the openings *d*, *d'*, *d''* into the flues 3, where it supports the combustion of the fuel (gas) admitted continuously through the nozzles *a*. The combustion gases travel downwardly 65 in said flues 3 and pass through the ducts 2 to the channels 1 from which they enter the primary regenerator *b* and pass to the chimney through the secondary regenerator *c*. 70

75 It will be understood that the gas remains turned on all the time and is fed continuously through the nozzles *a*, the reversal of the air current sufficing to direct the flow of 80 gas either into the flues 3 or into the flues 4.

I claim:

1. In a coke oven, a heating wall with parallel vertical flues arranged in independent pairs the two flues of the same pair being connected at different distances from one end of such pair by openings of a cross section diminishing progressively as their distances from said end increase, and with ducts located in each flue at the other end of 85 said pair for the admission of air and for the exit of combustion gases, and means for supplying fuel to the first-mentioned end of such pair.

2. In a coke oven, a heating wall with upright flues arranged in independent pairs, the two flues of the same pair being connected at different distances from one end of such pair by openings, and with ducts located in each flue at the other end for the 90 admission of air and for the exit of combustion gases, and means for supplying fuel to the first mentioned end of such pair.

3. In a coke oven, a heating wall with parallel flues arranged in separate pairs and provided, adjacent to one end and at different distances therefrom, with openings, of a cross section diminishing progressively as their distances from said end increase, by which the flues of the same pair communicate with each other, and with ducts located at the other ends of said flues for the admission of air and for the exit of combustion gases, and means for supplying fuel to the 105 first named flue ends.

110 In testimony whereof I have hereunto set my hand.

PAUL GOFFART.
